UNITED STATES PATENT OFFICE.

CLAIR DENNISON LAKE, OF BINGHAMTON, NEW YORK, ASSIGNOR TO THE TABULATING MACHINE COMPANY, A CORPORATION OF NEW JERSEY.

ATTACHMENT FOR CARD-SORTING MACHINES.

1,389,951.

Specification of Letters Patent. Patented Sept. 6, 1921.

Application filed September 24, 1920. Serial No. 412,571.

To all whom it may concern:

Be it known that I, CLAIR D. LAKE, a citizen of the United States, residing at Binghamton, in the county of Broome and State of New York, have invented certain new and useful Improvements in Attachments for Card-Sorting Machines, of which the following is a full, clear, and exact description.

10 The invention for which I now seek protection by Letters Patent is a new and useful attachment to the well known sorting machines for tabulator cards, such as are used in the Hollerith system. Such sorting 15 machines in themselves form no part of the present invention, but are, or may be, of the general character set forth in the patent to H. Hollerith, No. 1,237,646, dated August 21, 1917, and, in general terms, are characterized by the following features of construction and operation.

A bunch of cards, which are to be sorted according to certain index holes punched therein, are successively brought into operative or control position, and operate to set, by means of the punched record which they contain, devices which determine the point of delivery of each card, which devices remain so set while the cards are in transit 30 to the sorting stations where their delivery into appropriate compartments or receptacles is effected through the instrumentality of means controlled by such set devices.

The invention of this application is an improvement in attachments for such sorting machines whereby there may be selected from any number of sorted cards all cards of a given specific character without destroying the sequence of the sort of the remainder. Such a device is now known in the art as a card selector, and it may be adapted for use with one or any desired number of columns on a card in which index holes may be punched. I shall hereinafter 40 describe both a single and a multiple mechanism designed for this purpose.

The distinction between the device of this application and what are known in the art as card sorting machines may be further 50 gathered from the following: A card sorting machine is one that handles a promiscuous stack of cards. It has a single brush which is adjusted to position over a single vertical column of points for punched holes, so that

it sorts all the cards punched in such column into compartments or receptacles that correspond to the position of the punched holes. To sort order numbers, person numbers or anything else which have a plurality of figures, say four, requires four runs of the 60 cards to arrange them numerically, sorting first the ten-thousandths column, then the thousandths, then the hundredths and finally the units column, and the cards must be taken out of the compartments in such manner as not to mix them between sorts.

A card selector, on the other hand, is a device which takes any stack of cards and sorts out from the same all cards having holes corresponding to numbers, whether over one or more figures—that is to say, all cards of a special character and throws all others into a reject box or compartment. The selector is conveniently mounted on the frame of the sorter and is driven by the 70 driving mechanism of the same, and in thus selecting out special cards from any group, it does not disturb the order of the rejected or unselected cards. The purpose of the selector, in other words, is to select from a bunch of cards, whether they be arranged numerically or not, all cards punched the same in one or in a plurality of columns, without disturbing the sequence of the remainder.

In the accompanying drawings which illustrate the construction and the mode of operation of the above described attachment,

Figure 1 is a side view, mainly in elevation, of the interior mechanism of a casing containing the improvement.

Fig. 2 is a top, plan view of the said mechanism, the top of the casing being removed.

Fig. 3 is a front view of the same machine.

Fig. 4 is a detail of a stop lever.

Fig. 5 is a sectional detail of a ratchet and thumb operated gear wheel.

Fig. 6 is a detail view in elevation of one of the index wheels and its accessories.

Fig. 7 is a wiring diagram of the circuits and other parts used with the instrument.

Fig. 8 is a view similar to Fig. 1 but of a single column card selector.

Fig. 9 is a top plan view of such a card selector.

Fig. 10 is a view similar to Fig. 6 but amplified to show certain other parts, and

Fig. 11 is a wiring diagram for the single column card selector shown in Figs. 8 and 9.

I have used so far as is consistent with clearness of description the same reference numerals to indicate corresponding parts in the two machines.

Each selector comprises certain essential mechanical parts which may be first described. Referring, for example, to Figs.

10 1 and 2, which in this regard show merely a plurality of single column selectors, each of said selectors has two spring contacts 1, 2, secured to the insulating block 3 and forming terminals, and normally held apart by the tension of the springs. Under the free ends of these contacts is a contact cam 4 mounted on an insulating bushing 16 on a transverse shaft 5, and fixed to each bushing is a knurled setting wheel 6, an index wheel 7, and a driving pawl 8, —Fig. 6, —this combination of cam wheels and pawl being free to rotate on the shaft 5.

Within the index wheels 7 and fixed to the shaft 5 are ratchet wheels 9, Figs. 2 and 25 5, upon which rest and with which engage the pawls 8, and these ratchet wheels have teeth corresponding to and representing the figures in a column on the tabulator cards and those on the index wheels. The ratchet 80 wheels 9, being fixed on shaft 5, turn therewith and this shaft is driven by the sorting machine to which this instrument is adapted to be attached. It makes one complete revolution or cycle for each card that passes 85 through the sorter.

No more detailed description of the manner of attaching the device to a card sorter is required. Card sorting machines have a drive shaft which makes one revolution during the passage under the contact brush of each single card. The selecting device is mounted in any convenient manner on the frame of the card sorter, and the shaft 5 is geared or connected with the shaft of the 40 sorter, so as to revolve in unison therewith.

In conjunction with the wheels 6 there are employed thumb wheels 10 carried at the ends of levers 11 secured to a rock shaft 12 mounted on the frame of the machine. To 50 this shaft, lever 13, see Figs. 1 and 4, is fixed in such relation that when a projection 14 thereon drops or enters a notch 15 in the setting cam 17 secured to the shaft 5, the thumb wheel 10 meshes with the periphery of a setting wheel 6 and enables the operator to set or reset the contact cam 4 to exhibit the desired numeral or letter. It will, therefore, be understood from the construction above described that when the projection 60 14 on lever 13 enters the recess or notch 15 the index wheel 7 will show at a predetermined point the figure corresponding to the selected figure on a tabulator card.

With each of the above described combi-

nations is used a snap switch 18. In the case of a single column selector this switch, as is shown in the diagram Fig. 11, is employed to shunt the circuit around the contact combination when the apparatus is used for straight sorting. In the case of a multiple column selector the same switches as shown in the diagram Fig. 7 are used to shunt the circuit around the sorter magnet circuit relays for straight sorting.

The term "straight sorting" is a technical term in this art and by it is meant the sorting of all the cards which have a hole in a given vertical column. It will be seen, therefore, that when the sorter is used for straight sorting the contact combination in the single column selector or those in the multiple column selector are thrown out of operation as they are not needed.

The only remaining undescribed mechanical detail is what is known as the converting mechanism, which consists of a shaft 19 having on its end a knurled knob 20 and carrying two projections or fingers 21, Figs. 1, 2 and 7, of insulating material. When this shaft is turned these fingers engage with and hold closed the end contact combinations in order that the device may be used for straight sorting.

The cycle of operation of the single column selector will now be described by reference to the diagram Fig. 11. Switch 18 should be open. The operator first turns by hand the sorter to a position where the projection 14 enters the notch 15, thereby throwing the thumb wheel into gear with the setting wheel 6. He then, by means of the thumb wheel, sets the index wheel 7 so that any desired number, say 7, appears at the window of the device. The cards to be handled are then placed in the hopper of the sorter feed mechanism and the machine started. As the cards pass under the brush 22 the contact cam will bring the contacts 1 and 2 together at the 7 point, and when any card with a hole punched at 7 comes under the brush the circuit is completed through sorting magnet 23, which in a well understood way attracts its armature and stops the chute bars so that the card will go to the 7 box or receptacle. At no other time can the circuit to the sorting magnet be made, therefore the remainder of the cards in their order are guided into the reject box.

If it be desired to use the apparatus for straight sorting, the switch 18 is closed, with the result above described, and in such event the index wheel and cam attached may be in any position.

In a companion application, Serial No. 125 405,613, filed August 24, 1920, such parts of this diagram as are not described herein are more fully set forth, but for purposes of the present case a more complete understanding of the same is not essential.

If it be desired to select out from a stack of cards those having holes punched in given positions in a plurality of columns, then the multiple column selecting device which is used is that shown in Figs. 1, 2, and the circuits those of Fig. 7. Let it be assumed, for example, that all cards having punched in consecutive columns holes corresponding to 6893 are to be sorted out.

10 In this case the four selector index wheels are in the same way set by the thumb wheels to display at the windows the numerals 6893. The brush holders for the brushes 22 are then adjusted to the proper columns on the 15 cards, switches should be open, and the machine started.

As a card passes under the brushes the figure 9, or its equivalent hole assuming such hole to have been punched, will be the first to 20 permit a contact to be made between the brush for that column and the contact roll 24. Should this condition be established by the second brush from the end which corresponds to the tens position, a circuit would 25 be completed which energizes relays 25 and 26. The relay 25 is a shunt relay while relay 26 is a sorter magnet circuit relay, and the former thus closes a shunt around the brushes 22, through wires 27 and 28 and its own 30 armature through the relay 26 to the opposite terminal wire 29, which causes the circuit for that particular brush to remain closed after the brush has left the hole in the card until cam 30 breaks the circuit near 35 the end of the cycle. The contacts of the relay 26 are thus kept closed and bridge across its part of the sorter magnet circuit.

The same operation occurs at each of the other figures as they reach the brushes in 40 their part of the cycle, until the last break in the circuit of the sorter magnet 23 is bridged, when the machine acts in the same manner as a regular sorter. The last or lowest figure operating the sorting magnet stops 45 the chute bars for the card, and in this case being 3, the card selected for the figures 6893 will go into the 3 box or receptacle and all other cards in their order into the reject box.

Near the end of the cycle the shunt circuit 50 through wires 27, 28, is broken by a time controlled cam 30, when the device is ready for another card. It is manifest that the combination of circuits closed by the holes provided to correspond with 6893 will not be 55 closed by any other figure and hence all other cards will go to the reject box.

The brush holders or carriers are individual and may be thrown out at will, but the switches 18 are for the purpose of bypassing the contact combinations, as is clearly indicated in the diagram, Fig. 7.

Should it be desired to use the device for straight sorting, either of the two outside brushes, according to which end of the sorter feed mechanism the brush holder is set, may

be used, as the converting mechanism, comprising the shaft 19 and finger 21, operates on the outside contact combinations only and thus closes these two contacts. The remaining center brushes and the other outside 70 brush, not being used, can either be thrown out or left in, as desired. The four index wheels and cams also may be in any position, and one switch 18, corresponding to the brush being used, should be open, while the 75 other three switches should be closed.

The above described apparatus has been found in practice to be a most valuable and useful accessory to the ordinary card sorting machines. It greatly widens their field of 80 usefulness and simplifies many operations where it is desirable to distinguish and to select out all cards of a certain character.

What I claim is:

1. In an attachment for and driven by a 85 card-sorting machine, the combination with normally separated contacts adapted to be connected up in the circuit of the sorting magnet, a cam and index wheel with divisions corresponding to the horizontal lines 90 for punched holes in a card, and means for adjusting said cam and index wheel to close the contacts at any given point in the cycle, whereby only such cards as have holes corresponding to such adjusted position will be 95 sorted out.

2. In an attachment for and driven by a card-sorting machine, the combination with a plurality of pairs of normally separated contacts, circuits adapted to be closed by 100 the same, relays in said circuits adapted when energized to close breaks in the circuit of the sorting magnet, cams and index wheels with divisions corresponding to the horizontal lines for punched holes in a card, 105 and means for adjusting said cams and index wheels to close the contacts at predetermined points in the cycle whereby the sorter magnet circuit will be completed when all 110 of the contacts corresponding to such adjusted positions have been closed, and only such cards as have holes corresponding to such adjusted positions will be sorted out.

3. In an attachment for and driven by a 115 card-sorting machine, the combination with a plurality of pairs of normally separated contacts adapted to be connected up in circuit with the sorting magnet, cams for operating said contacts, index wheels (with divisions corresponding to the horizontal 120 lines for punched holes in a card) secured to said cams, a driving pawl secured to each index wheel, ratchets (with teeth corresponding to the divisions on the index 125 wheels) secured to a shaft, a notched disk or cam secured to said shaft, a lever with a projection thereon adapted to be brought into engagement with the notch, and thumb wheels operated by said lever and adapted to be brought into gear with the index 130

wheels when the projection lies in the said notch, whereby the index wheels may be adjusted from outside the device.

4. In an attachment for and driven by a card-sorting machine, the combination with a plurality of normally open contacts, a cam for closing each pair, an index wheel secured to each cam, circuits adapted to be completed by the contacts, relays in said circuits which when energized close breaks in a circuit including the sorting magnet, means for adjusting the cams and index wheels so that the contacts will be closed at predetermined instants in the cycle, and means for breaking all circuits at the end of each cycle.

5. In an attachment for and driven by a

card-sorting machine, the combination with normally open contacts adapted to control the sorting magnet circuit, adjustable cams for closing said contacts at predetermined instants in the cycle, and switches for rendering inoperative the said contacts when so desired.

6. In an attachment for and driven by a card-sorting machine, the combination of controlling contacts for the sorting magnet, of adjustable cams adapted to be set so as to operate said contacts at predetermined instants in each cycle of operation.

In testimony whereof I hereto affix my signature.

CLAIR DENNISON LAKE
